CALCULATING APPARATUS

Application filed February 9, 1928, Serial No. 87,120, and in Norway February 10, 1925.

My invention relates to calculating apparatus of the type comprising a series of indicating discs rotatably mounted on axes in spaced relation to each other, with intermediate driving devices interposed between successive discs, each arranged to be driven by the disc to its right in the series and arranged to drive the disc to its left. It is the object of my invention to provide improved intermediate driving devices adapted to cooperate with suitable justifying means whereby the indicating disc at the end of the series can be given a complete single step movement in either direction by power applied to the indicating disc at the opposite end of the series with the power acting through only a similar single step distance. For accomplishing this object, I have provided intermediate rotary driving devices, each having short broad tooth portions by which power is applied to the device from the indicating disc at the right and having comparatively longer and narrower tooth portions projecting outwardly in centered position with respect to the short broad tooth portions for applying power from the device to the indicating disc at the left.

It is another object of my invention to improve devices of this type in sundry details hereinafter pointed out. The preferred means by which I have accomplished my objects are illustrated in the drawing and are hereinafter specifically described. That which I believe to be new is set forth in the claims.

On the drawing Fig. 1 is a plan view of one form of the invention, parts of the apparatus being broken away in such a manner that the right hand side of Fig. 1 marked H illustrates a plan of the complete apparatus, whereas the middle part, marked M is shown with the top covering removed and the left hand side comprising the three left hand wheels is illustrated with also the numeral discs removed.

Fig. 2 shows a partial vertical longitudinal section through the axes of the numeral discs and Fig. 3 shows a vertical cross section taken through the axis of a numeral disc.

The calculating apparatus as will be seen

on the drawing comprises a number of numeral discs *n* mounted on shafts *m*. Each numeral disc preferably has a polygonal or toothed circumference, said discs being acted upon by springs *f* which serve to hold them 55 yieldingly in certain determined positions.

On its top surface each numeral disc is provided with the numbers 0 to 9 printed at distances in a circle and radially outwards of the numbers the disc is provided with recesses or holes *h*. The cover *k* is provided with segmental slots *l* through which the holes *h* can be seen and further with openings *o* through which can be seen one of the numbers printed on the top surface of the 65 disc.

On the same shaft *m* as each numeral disc is mounted a gear *b* as well as a single tooth or finger *c*. Between each pair of shafts *m* and on one side of the line of shafts there are 70 mounted toothed wheels *d*, each adapted to engage the gear *b* to the left and to be engaged by a tooth *c* to the right. Each of the gears *b* is located in the same horizontal plane with the toothed wheel *d* to the right, whereas 75 the toothed wheel *d* to the left is mounted either higher or lower so that no engagement can take place. The tooth *c* is mounted so as to engage the toothed wheel *d* to the left, whereas the toothed wheel *d* to the right lies 80 either above or below it so that no engagement between the tooth and that toothed wheel can take place.

As will be seen on the drawing the tooth *c* is integral with gear *b*, being however bent 85 so as to be out of the plane of the teeth on said gear *b*. The arrangement as above described is effected by inverting each gear *b* as compared with the adjacent gears *b*, and inverting each wheel *d* as compared with the adjacent wheels *d*, the gears *b* being all alike and the wheels *d* being all alike whereby the cost 90 of manufacture is kept down.

The toothed wheels *d* are also provided with springs *g* carried by the casing and having their free end portions in engagement with the teeth of the wheels for holding the wheels yieldingly in predetermined adjusted positions. As will be readily understood, the springs *f* and *g* serve both as justifying 95 100

means for assuring that the gears *b* and *d* stop in the desired angular positions and also as auxiliary actuating means for the transmission of power from one member to another, as is usual in mechanisms of this type.

By the use of the construction shown, involving the use of short broad tooth portions on the intermediate driving device *d* for engagement by the tooth or finger *c* of the indicating disc to the right, and the use of comparatively much longer and narrower tooth portions extending beyond the short broad tooth portions in centered position with respect thereto for engaging the teeth of the gear of the indicating disc to the left, I am enabled to provide a structure comprising a comparatively small number of parts so arranged with respect to each other as to have efficient cooperation by which power applied to the indicating disc at the extreme right serving to give said disc one-tenth of a complete rotation may be transmitted through the entire train of mechanism for giving the indicating disc at the extreme left a similar movement comprising one-tenth of a complete rotation. This situation would, of course, arise when 1 would be added to 999,999.

On shafts *m* above the gears *b* there are mounted toothed wheels *e*, which are adapted to be engaged by a rack *a*, which is slidably mounted along one side of the apparatus-casing and can be reciprocated by hand in order to bring all discs back to their zero position after a calculating operation has been performed.

For this purpose each toothed wheel *e* has no teeth on the part which is nearest rack *a*, when the disc *n* is in zero-position. Also rack *a* has a gap in its row of teeth adjacent each wheel *e* so that the wheels *e* can turn freely on gear shafts when rack *a* is in its normal position.

The operation of the calculating apparatus will be understood from a description of the operation for adding 75 and 25.

First the rack *a* is reciprocated in order to make sure that all numeral discs are in zero-position. Then a stylus is placed in the hole 50 of the right hand or units disc, which corresponds to number 5 in the inner row of numbers on the cover and the disc is turned in clockwise direction in Fig. 1 until the stylus stops at the end of the slot *l*. Then the same 55 operation is performed with the second or tens disc, using the hole outwards of number 7 in said inner row, and when this has been done, the number 75 can be seen in the two right hand holes *o* of the cover. To add 25 60 the operation described above is repeated first with the hole corresponding to the number 5 of the inner row at the right hand disc and then with the hole corresponding to the number 2 of said inner row on the next disc. The 65 result is to make number 0 visible in the right

hand hole *o*, and at the same time as the indicating disc at the right is passing the critical point with respect to the complete set of indicia thereon the carrying wheel *d* is moved one step by means of tooth *c* for moving the tens disc one step forward so as to show number 8 through its opening *o*. When the tens disc showing the number 8 is moved two steps farther as above indicated the numeral 0 will be seen in the opening for this numeral disc too, the carrying device having acted upon the hundreds disc for moving it one step forward so that the number 100 is seen in the three right hand openings *o* of the cover.

In order to move the numeral discs back to zero position after having carried out the addition, the rack *a* is reciprocated in the manner referred to above.

In order to use this calculating apparatus 85 for subtraction the numeral discs must be turned in the opposite direction, using the rows of numbers printed on the cover outside of the slots 1.

In the construction shown, each of the numeral discs *n* is provided with a single set of indicia from 0 to 9 corresponding to the single tooth *c* carried by the attached gear *b*. I do not restrict the invention to the use of a single tooth *c*, it being understood that 95 a different number of teeth *c* might be employed with a corresponding number of sets of indicia. Neither is the invention to be limited to the details of construction as shown except so far as the claims may be so limited 100 ed by the prior art.

It will be understood that the arrangement involving the short broad tooth portions and the centrally arranged longer and narrower tooth portions on the intermediate driving devices *d* is provided particularly with reference to the successful transmission of power through a train comprising a considerable number of indicating discs and gears. It will be appreciated that the claims are to be construed in the light of the possibilities of the mechanism when used in an extended train of gearing even though the claims are not limited in terms to such use.

Claims:—

1. In a device of the class described, the combination of indicating discs rotatably mounted on axes in spaced relation to each other, a gear connected with one of said indicating discs for rotation therewith, a finger connected with the other of said indicating discs for movement therewith, and toothed driving means rotatably mounted in operative relation to both said gear and said finger and comprising broad tooth portions with which said finger engages for rotating the driving device and comparatively longer and narrower tooth portions extending beyond the broad tooth portions adapted by engage- 130

ment with said gear to drive the gear and connected indicating disc.

2. In a device of the class described, the combination of indicating discs rotatably mounted on axes in spaced relation to each other, a gear connected with one of said indicating discs for rotation therewith, a finger connected with the other of said indicating discs for movement therewith in the same plane with said gear, and a toothed driving device rotatably mounted in operative relationship to both said gear and said finger and comprising broad tooth portions of such length as to clear said gear upon the rotation of the driving device but engageable by said finger for actuation of the driving device thereby and comprising also comparatively longer and narrower tooth portions extending outwardly beyond the broad tooth portions in centered relation thereto adapted by engagement with said gear upon the rotation of the driving device to drive the gear and the connected indicating disc.

In testimony that I claim the foregoing as my invention, I have signed my name.
